BEER FAUCET

Louis F. Vetrano, Oakland, Calif., assignor of
three-fourths to William J. Pugh, Oakland,
Calif.

Application April 3, 1947, Serial No. 739,111

9 Claims. (Cl. 225—5)

1

This invention relates to beer faucets, and the principal object thereof is to provide a faucet embodying certain novel features of construction hereinafter set forth.

I will explain the invention with reference to the accompanying drawing, which illustrates one practical embodiment thereof, to enable others to adopt and use the same, and will summarize in the claims the novel features of construction, and novel combinations of parts, for which protection is desired.

In said drawing:

Figure 1 is a vertical section through a beer faucet and beer glass applied thereto, showing in full lines the valve in closed position, and indicating in dotted lines one partly-open position of the valve.

Fig. 2 is a vertical section similar to Fig. 1, but showing the valve in another opened position.

As shown, the valve preferably comprises a base 1 having a disc-like lower surface 1a which may be covered by a pad 2 of felt or the like for engagement with the upper end of the beer glass G positioned thereunder, as shown.

The felt or other pad 2 which is provided on the underside of the lower surface of base 1 will serve to prevent breakage of the glass. Base 1 is provided with a depending tubular portion 3 extending downwardly and centrally of the lower surface 1a, said tubular portion 3 being of length slightly less than the depth of the glass G, and hence terminating adjacent the lower end of said glass. The lower end of the tubular portion 3 is threaded as at 3a and adapted to receive a plug 4 which is externally threaded and which carries a conical valve seat 4a, the lower end of which terminates in a reduced axial bore 4b. Plug 4 is therefore readily demountable and replaceable in tubular portion 3.

Extending axially of the tubular portion 3 is a valve stem 5 slidable in guide spiders 6 within the tubular portion 3, said stem 5 carrying a ball valve 7 at its lower end adapted in one position of the stem to engage valve seat 4a of plug 4. The upper end of the tubular portion 3 terminates in a parti-tubular horizontal bearing for a rocker shaft 8 making a fluid-tight fit therein, said shaft 8 carrying a handle 9 provided with a head 9a, whereby the shaft 8 may be manually rotated in the base 1. The side of the bearing opposite the handle 9 is recessed as at 8a and carries a short arm 10 which is pivotally connected to the upper end of a link 11, the lower end of which link is pivotally connected to the upper end of the valve stem 5. The arm 10 and link 11 are of such

2

length that when the handle 9 is in the vertical position, shown in full lines in Fig. 1, the ball valve 7 will firmly contact the valve seat 4a and prevent passage of beer through the lower end 5 of the tubular portion 3 into the glass G, the beer being introduced into the upper end of tubular portion 3 through a pipe 12 connected with the beer usual or customary cooling coils C.

The swinging movement of arm 10 is limited by 10 a pair of abutments on base 1, one abutment 1x being adapted to contact the handle 9 when swung into the position shown in dotted lines in Fig. 1, at which time the ball valve 7 will be slightly raised off of the valve seat 4a into the position 15 shown in dotted lines, Fig. 1. The base 1 also carries an abutment 1y adapted to engage the handle 9 when swung into the position shown in Fig. 2, at which time the valve 7 will be sufficiently raised above the valve seat 4a to permit 20 substantially unrestricted flow of beer through the lower end of tubular portion 3.

When the handle 9 contacts abutment 1x, the ball valve 7 will be slightly unseated, allowing a small amount of beer to flow into glass G, i. e., 25 up to the dotted line G' (Fig. 1) thereby submerging the lower end of the tubular portion 3 below the beer level denoted by the dotted line G', thus preventing air from reaching the beer.

After glass G has been thus partially filled, up 30 to the line G', the bar tender will then throw handle 9 into the position shown in Fig. 2, i. e., into contact with the abutment 1y, thereby allowing a full flow of beer down through the tubular portion 3 and through the orifice 4b in the 35 plug 4, which is preferably approximately $\frac{5}{8}$ inch in diameter, and thus permitting the bar tender to draw a full glass of beer or foam to any level of the glass G, such as to the level of dotted line G2 (Fig. 2) or any other desired level.

40 By the above construction the bartender, by utilizing the two open positions of the handle 9, may draw a glass of beer with any desired head of foam.

I do not limit my invention to the exact forms 45 shown in the drawing, for obviously changes may be made therein within the scope of the claims.

I claim:

50 1. In a beer faucet, a base; a tubular portion depending from the base and of length slightly less than the depth of an ordinary beer glass, said tubular portion having an inlet at its upper end for beer from a source of supply; a valve seat in the lower end of the tubular portion terminating in a reduced bore; a valve stem within said tubular portion having a ball valve on its lower end

adapted to engage said seat; a handle having a hub closing the upper end of the tubular portion, said hub having a recess opposite the tubular portion; an arm within said recess; a link pivotally connected to the arm and to the stem, said arm and stem being of such length that when same are aligned with the stem the ball valve will firmly contact said seat; and a pair of abutments on said base adapted to be engaged by the handle whereby when same engages one said abutment the valve will be slightly unseated, and when same engages the other abutment the valve will be entirely unseated.

2. In a faucet as set forth in claim 1, said abutments being formed at the ends of a cut-out portion of the base through which the handle projects.

3. In a beer faucet, a base; a tubular portion depending from the base and of length slightly less than the depth of an ordinary beer glass, said tubular portion having an inlet at its upper end for beer from a source of supply; a removable plug in the lower end of the tubular portion having a valve seat in its upper end terminating in a reduced bore opening at the lower end of the plug; a valve stem within said tubular portion having a ball valve on its lower end adapted to engage said seat; a handle having a hub closing the upper end of the tubular portion, said hub having a recess opposite the tubular portion; an arm within said recess; a link pivotally connected to the arm and to the stem, said arm and stem being of such length that when same are aligned with the stem the ball valve will firmly contact said seat; and a pair of abutments on said base adapted to be engaged by the handle whereby when same engages one said abutment the valve will be slightly unseated, and when same engages the other abutment the valve will be entirely unseated.

4. In a faucet as set forth in claim 3, said lower end of the tubular portion being trapped; and said plug being threaded thereinto.

5. In a faucet as set forth in claim 3, said abutments being formed at the ends of a cut-out

portion of the base through which the handle projects.

6. In a beer faucet, a base having a disc-like lower surface; a tubular portion depending from the base centrally of the lower surface thereof and of length slightly less than the depth of an ordinary beer glass, said tubular portion having an inlet at its upper end for beer from a source of supply; a plug in the lower end of the tubular portion having a valve seat in its upper end terminating in a reduced bore opening at the lower end of the plug; a valve stem within said tubular portion having a ball valve on its lower end adapted to engage said seat; a handle having a hub closing the upper end of the tubular portion, said hub having a recess opposite the tubular portion, an arm within said recess; a link pivotally connected to the arm and to the stem, said arm and stem being of such length that when same are aligned with the stem the ball valve will firmly contact said seat; and a pair of abutments on said base adapted to be engaged by the handle whereby when same engages one said abutment the valve will be slightly unseated, and when same engages the other abutment the valve will be entirely unseated.

7. In a faucet as set forth in claim 6, a pad of soft material on the underside of the lower surface of the base.

8. In a faucet as set forth in claim 6, said lower end of the tubular portion being tapped and said plug being threaded thereinto.

9. In a faucet as set forth in claim 6, said abutments being formed at the ends of a cut-out portion of the base through which the handle projects.
